(57) **CLAIM**

The ornamental design for a tray, as shown and described.

DESCRIPTION

FIG. 1 is a perspective view of a tray showing a first
embodiment of our new and ornamental design;

FIG. 2 is an alternate perspective view thereof;

FIG. 3 is a bottom plan view thereof;

FIG. 4 is a top plan view thereof;

FIG. 5 is a rear elevation view thereof;

FIG. 6 is a front elevation view thereof;

FIG. 7 is a side elevation view thereof;

FIG. 8 is an opposite side view thereof;

FIG. 9 is a perspective view of a tray showing a second
embodiment of our new and ornamental design;

FIG. 10 is an alternate perspective view thereof;

FIG. 11 is a bottom plan view thereof;

FIG. 12 is a top plan view thereof;

FIG. 13 is a rear elevation view thereof;

FIG. 14 is a front elevation view thereof;

FIG. 15 is a side elevation view thereof;

FIG. 16 is an opposite side view thereof.

FIG. 17 is a perspective view of a tray showing a third
embodiment of our new and ornamental design;

FIG. 18 is an alternate perspective view thereof;

FIG. 19 is a bottom plan view thereof; and,

FIG. 20 is a top plan view thereof.

(Continued)

The broken lines in the drawings depict portions of the tray that form no part of the claimed design.

1 Claim, 20 Drawing Sheets
